UNITED STATES PATENT OFFICE.

HUDSON MAXIM, OF NEW YORK, N. Y.

CARTRIDGE.

SPECIFICATION forming part of Letters Patent No. 694,295, dated February 25, 1902.

Application filed August 24, 1899. Serial No. 728,304. (No model.)

To all whom it may concern:

Be it known that I, HUDSON MAXIM, a citizen of the United States of America, and a resident of the borough of Manhattan, city, county, and State of New York, have invented a new and useful Improvement in Cartridges, which invention is fully set forth in the following specification.

The present invention relates to improvements in cartridges, and has for its object, mainly, to provide a charge of explosive material for guns which may be handled integrally and may, if desired, be employed with the projectile attached thereto as fixed ammunition, and which charge shall also present to the flame of ignition the minimum of burning-surface and be consumed with such increase of burning areas as to produce the desired acceleration and secure the highest ballistic results.

In carrying out my invention I arrange a plurality of cylinders of explosive material, one within another, each of the interior cylinders being enough smaller than the cylinder inclosing it to permit one being inserted within the other and to provide a passage between them for the ignition-flame and the products of combustion, thus forming a cylindrical mass of powder having longitudinal demarcations extending therethrough. The several cylinders composing the charge may be, and preferably are, connected together and are perforated transversely, preferably radially, with a sufficient number of uniformly-disposed holes to provide for the lateral venting of the gases of combustion from the cylinders to prevent their disruption by said gases and also to provide for suitable burning thicknesses between the perforations to secure the simultaneous completion of the combustion throughout the mass of the explosive. The outer tubes being larger than those which are inclosed are provided with a correspondingly-larger number of perforations. Concentrically arranged tubes, perforated as described, constitute a charge especially adapted to secure progressive combustion. These tubes may be made either by stuffing or by forming into sheets and then rolling into cylinders, or the entire charge may be made into a multiperforated sheet and rolled upon itself, and this may or may not

be placed concentrically within a multiperforated tube. Instead of extending entirely through the walls of the cylinders some of the 55 perforations in the form of cells may extend but part way through.

An essential feature of the invention consists in arranging cylinders of explosive material so as to provide longitudinal demarcations through the charge, in combination with lateral perforations, the demarcations being preferably such as to provide greater burning-surfaces than the lateral perforations, but usually of such length as to require additional outlets for the gases of combustion in order to avoid the disruption of the charge by such gases. For this reason the lateral perforations are made to enter the longitudinal demarcations and may extend through 70 such demarcations into the mass of the next interior cylinder or even through both cylinders. It will be readily understood that the entire charge may be composed of a single set of cylinders of explosive material, as above 75 described, or be made up of a plurality of such sets of cylinders, either tied together in a bundle or fagot or cemented together, as desired.

When a projectile is employed as an integral part of the cartridge as fixed ammunition, the outer tube or cylinder is made to extend over a portion of the projectile—that is to say, the charge is formed with a cup at its forward end for the reception of the projectile, 85 and the projectile may be seated and secured therein in any suitable manner, being preferably seated deep within the charge to secure greater rigidity.

In the accompanying drawings I have for 90 the purpose of illustrating the inventive idea shown some of the forms which the invention may assume; but such drawings are to be understood as for the purpose of illustration only and not as defining the limits of the 95 invention.

In said drawings, Figure 1 is a transverse sectional view of a charge composed of cylinders of explosive material arranged according to my invention and in which all the cylinders except the outer one are transversely perforated, while the outer cylinder is provided with inwardly-opening cells which do not extend through the cylinder. Fig. 2 is

an end view, partly in section, in which all the cylinders are transversely perforated. Fig. 3 is a like view showing one arrangement of cells and transverse perforations that may be adopted. Fig. 4 is an end view of a charge, showing one form of longitudinal demarcations between the several cylinders, and Fig. 5 is a like view of still another form. Fig. 6 is an end view, partly in section, showing the manner of forming the charge by rolling a perforated sheet upon itself. Fig. 7 is a longitudinal section of a charge with its attached projectile in place in the charge-chamber of a gun; and Fig. 8 is a longitudinal section of a charge and its attached projectile, showing a somewhat different arrangement of the perforations in the adjacent cylinders of the charge.

Referring to Fig. 1, the charge consists of a plurality of closely-fitting concentric tubes of successive sizes. In this form the tubes are made of sheets of transversely perforated explosive material cut to the proper length and rolled in the form of cylinders, the joints of which are arranged to alternate or to otherwise break joints when the tubes are assembled. The distance between the perforations 3 in all the tubes is substantially uniform, and from this it will be understood that the larger tubes will have correspondingly a greater number of perforations. Upon firing the charge the igniting-flash will traverse the large central opening 4 and also the spaces or demarcations between the tubes, which, however, may be exceedingly small and ordinarily provided for by the slight irregularities of the surface of the material. In order to prevent too great an erosion of the walls of the powder-chamber in which the charge may be placed by the gases of combustion escaping from the perforations, the outer tube 5 in this case is not perforated, but provided with a corresponding number of cells 6 on its inner surface, which extend into the layer of explosive material a sufficient depth to leave an unperforated layer of such thickness as to be consumed simultaneously with the complete combustion of the remainder of the charge.

Fig. 3 shows a form of the charge composed of a plurality of layers of comparative greater thickness than those in the preceding forms and provided with radial perforations 3 and cells 10 of varying lengths extending from the outer surface of the charge partially through the body of the material. In this way initial burning-surface is uniformly distributed by radial perforations and cells in the body of the charge without recourse to a great number of layers.

The modification shown in Fig. 4 consists of a series of concentric tubes 1, provided with longitudinal ribs 13, which serve to separate the tubes and to provide longitudinal perforations for the same purpose as those shown in Fig. 7.

Fig. 5 illustrates an end view of a charge

of concentric layers and in which the tubes are separated by a comparatively small layer 14 of quickly-burning material, such as a 70 suitable flash charge.

In the form shown in Fig. 2 the charge is also made of concentric tubes 1, which are, however, in this case seamless and are all perforated instead of having cells in the 75 outer cylinder, as in Fig. 1.

Fig. 6 illustrates the charge made of a continuous perforated sheet 7, rolled in the form of spiral when viewed end on, and preferably bound by a cord 8, of any suitable material. 80

In all of the foregoing forms the perforations are of such dimensions and relative arrangement as to provide a uniform thickness of material between them, so as to cause the simultaneous completion of combustion of the 85 explosive throughout the mass.

The charge or cartridge, combined with a projectile and placed in a gun 22, is shown in Fig. 7. The explosive charge 23 may be any one of the forms before described, with one or more of its outer layers extending beyond the main body of the charge and surrounding the projectile 24, which is held more securely in position by having the explosive charge shrunk and cemented to it. By this 95 construction the propulsive charge and projectile may be handled in one piece and the loading of a gun separately with projectile and powder charge avoided. It also has the advantage of dispensing with an inclosing case, which 100 has to be removed from the gun before a new cartridge can be inserted. The actual loading of a gun is therefore the only operation to be performed, and consequently the rate of fire may be greatly increased. 105

The front end 25 of the charge is preferably beveled to approximately fit the contraction of the powder charge to the rifled portion 26 of the gun. At this point the projectile is provided with a metallic ring 27, serving as a 110 driving-ring and as a guiding-ring, and also with an obturating-ring 28, directly in the rear of the driving-ring. A similar driving-ring 30 and obturating-ring 31 is constructed around the base of the projectile, which upon 115 reaching the lands of the gun assume the function of rotating the projectile and preventing escape of powder-gases jointly with the forward driving-ring and obturating-ring.

The interior of the propulsive charge contains a flash charge 32, which is sealed in the inner tube by a thin layer 33 of easily-ignited or explosive material lying opposite the firing device 34 in the breech-block 35. 120

In Fig. 8 the cartridge is shown with the projectile in longitudinal section. In this case the flash charge is sealed by a thin inverted cup 36, of any suitable material, such as paper or cloth, inserted in the central opening and lying flush with base of the charge. 125

Having thus described my invention, I claim—

1. In a cartridge charge, a plurality of concentrically-arranged integral cylinders of ex-

plosive material with longitudinal demarcations constituting a flame-passage between the cylinders and a plurality of symmetrically-arranged lateral vents to said demarcations.

5 2. In a cartridge charge, a plurality of integral cylinders of explosive material arranged one within the other with longitudinal demarcations constituting a flame-passage between the cylinders and lateral vents to said demarcations.

10 3. In a cartridge charge, a plurality of integral cylinders of explosive material arranged one within the other with longitudinal demarcations constituting a flame-passage between the cylinders, lateral vents to said demarcations, and laterally-opening cells formed in the walls of the cylinders.

15 4. In a cartridge charge, a plurality of integral cylinders of explosive material arranged one within the other with longitudinal demarcations constituting a flame-passage between the cylinders, a plurality of symmetrically-arranged vents to said demarcations and a plurality of symmetrically-arranged laterally-opening cells formed in the walls of the cylinders.

20 5. In a cartridge charge, a plurality of integral cylinders of explosive material arranged one within the other with longitudinal demarcations constituting a flame-passage between the cylinders and lateral vents to said demarcations, and a projectile seated in and surrounded by one of said cylinders.

25 6. In a cartridge charge, a plurality of integral cylinders of explosive material provided with lateral vents and laterally-opening cells, said vents and cells being arranged equidistant from each other on any given surface of any given cylinder.

30 7. In a cartridge charge, an integral cylinder of explosive material having a longitudinal perforation therethrough and lateral vents to said longitudinal perforation; a second integral cylinder surrounding the first with a longitudinally-extending demarcation constituting a flame-passage between them.

35 45

and a plurality of symmetrically-arranged lateral vents to said demarcation.

8. In a cartridge charge, an integral cylinder of explosive material having a longitudinal perforation, a second integral cylinder surrounding the first but with a longitudinally-extending demarcation constituting a flame-passage between them, and a plurality of symmetrically-arranged lateral vents extending from said perforation through said cylinders.

9. In a cartridge charge, an integral cylinder of explosive material having a longitudinal perforation, a second integral cylinder surrounding the first and having a longitudinally-extending demarcation constituting a flame-passage between them, each of said cylinders being provided with a plurality of symmetrically-arranged lateral vents.

10. In a cartridge charge, an integral cylinder of explosive material having a longitudinal perforation, a second integral cylinder surrounding the first and having a longitudinally-extending demarcation constituting a flame-passage between them, each of said cylinders being provided with a plurality of symmetrically-arranged lateral vents and a plurality of laterally-opening cells.

11. In a cartridge charge, an integral cylinder of explosive material having a longitudinal perforation, a second integral cylinder surrounding the first and having a longitudinally-extending demarcation constituting a flame-passage between them, each of said cylinders being provided with a plurality of symmetrically-arranged lateral vents and a plurality of symmetrically-arranged laterally-opening cells.

In testimony whereof I, HUDSON MAXIM, have signed this specification in the presence of two subscribing witnesses.

HUDSON MAXIM.
